(57) **CLAIM**

The ornamental design for a table, as shown and described.

DESCRIPTION

FIG. 1 is a perspective view of the design of my table;

FIG. 2 is a right-side elevation view thereof;

FIG. 3 is a left-side elevation view thereof;

FIG. 4 is a front elevation view thereof;

FIG. 5 is a back elevation view thereof;

FIG. 6 is a top plan view thereof; and,

FIG. 7 is a bottom plan view thereof.

The broken lines represent portions of the table that form no part of the claimed design. The dot-dash broken lines define

(Continued)

the bounds of the claimed design and form no part thereof. The claimed design extends to but does not include the boundary line.

1 Claim, 6 Drawing Sheets
